UNITED STATES PATENT OFFICE.

BENJAMIN C. PERKINS, OF HARTFORD, CONNECTICUT, ASSIGNOR TO THE ARROW ELECTRIC COMPANY, OF HARTFORD, CONNECTICUT, A CORPORATION OF CONNECTICUT.

LUMINOUS ATTACHMENT FOR ELECTRIC-SWITCH-OPERATING MEMBERS.

Application filed June 27, 1922. Serial No. 571,137.

To all whom it may concern:

Be it known that I, BENJAMIN C. PERKINS, a citizen of the United States of America, residing in Hartford, in the county of Hartford and State of Connecticut, have invented certain new and useful Improvements in Luminous Attachments for Electric-Switch-Operating Members, of which the following is a specification.

10 My invention relates to a luminous attachment for an electric switch operating member, and the object of my invention is to provide a luminous attachment of such character that it may be applied to switch 15 operating members of different types adapted to receive it, and preferably to associate with the attachment means for locking it against escape from the switch operating member. The invention is susceptible of 20 embodiment in various forms, not only with respect to the luminous element of the attachment, but also with respect to the means by which it is secured to the switch operating member. I have shown only certain 25 illustrative embodiments thereof in the accompanying drawings, in which—

Fig. 1 is a plan view of an electric switch, to the operating lever of which my invention is applied in one form;

30 Fig. 2 is an enlarged side elevation of the switch operating lever illustrated in Fig. 1;

Fig. 3 is a broken elevation thereof at right angles to position shown in Fig. 2;

35 Fig. 4 is a section on the line 4—4, Fig. 2;

Fig. 5 is a broken side elevation of a modified form of luminous attachment and a corresponding modification of the switch lever to cooperate therewith;

40 Fig. 6 is a section on the line 6—6, Fig. 5;

Fig. 7 is a plan view of a locking washer;

Fig. 8 is an inverted plan of the luminous attachment alone;

45 Fig. 9 is an enlarged section on the line 9—9, Fig. 7;

Fig. 10 is a side elevation partially in section of a modified form of switch lever;

Fig. 11 is a section through the end of a switch operating pull chain to which a luminous attachment of the type shown in Fig. 6 is applied; and

50 Fig. 12 is a similar view of the end of a switch operating pull cord.

Various types of luminous elements for

electric switch operating members have been 55 provided, but so far as I am aware they necessitate either a special construction of the operating member, with which the luminous element is permanently associated as a structural element, or where the 60 luminous member is independent and removably applied, a special construction is necessitated, which not only adds materially to the cost of the switch operating member, but also disfigures it when a luminous attachment 65 is not used. Moreover, such independent attachments as have been provided heretofore are readily detached, and are frequently stolen when exposed in public 70 places, such as hotel rooms, offices, etc. By 75 the present invention I provide a luminous attachment which may readily be applied to a switch operating member and secured thereto by means which are impossible or difficult of release, but which involve very slight additional expense in the manufacture 80 of the switch operating member, and moreover, do not detract in any way from its appearance, but, on the contrary, add to its normal attractiveness, when the luminous 85 attachment is not in position.

In the form of construction shown in Figs. 1—4, I have shown the attachment applied to the manipulating end 15 of the operating lever 16 for a toggle switch housed 85 beneath the usual face plate 17. It is customary, in the majority of switches of this type, to impart to the end 15 of the lever a more or less conical contour with rounded head of greater diameter than the shank. 90 This is well adapted for the reception of the present luminous attachment 18, which is here shown in the form of a cap having a skirt-like extension slotted to form spring fingers 19 which embrace the head of the lever, and having an oppositely projecting luminous element 20 which may be of any suitable character. While the spring fingers 19 will serve alone to hold the cap 18 in position on the lever, it is desirable to provide the head of the latter with a lateral fillet area 21, and to form the ends of the spring fingers 19 with locking dogs 22 which enter the channels between the fillets. The engagement between the dogs 22 and the 95 fillets 21 effectively locks the cap in position on the lever and prevents its removal without such a distortion of the fingers 19 as

renders the re-use of the attachment impractical. The fillets 21, far from detracting from the appearance of the lever, actually serve to ornament it, and add to its attractiveness. Consequently, even if the luminous attachment is not used the appearance of the switch lever is not objectionably affected.

In Figs. 5 to 9 I have shown a modified construction in which the lateral fillet on the head of the lever is in the form of a spiral or thread 23, while the luminous attachment 24 has an internally threaded skirt or annular flange 25. The threaded engagement thus afforded is sufficient to secure the attachment on the lever end, but would not in itself prevent the ready removal of the cap therefrom. In order to prevent such removal I preferably form in the dome-like head of the lever 15 a series of radial serrations 26, or their equivalents. A second series of serrations 27, or their equivalents, is formed on the inner face of the cap 24. A lock washer 28, preferably resilient, which may be permanently, but loosely, staked at 29 in the cap 24 by deforming portion of the wall above the margin of the washer, is provided with dogs 30 and 31 offset from opposite faces of the washer and adapted to engage the serrations 26 and 27, respectively, on the dome of the switch lever, and on the inner face of the cap 24 when the attachment is screwed into position on the lever. The dogs 30 and 31 are faced in such direction that they permit the cap to be screwed down hard upon the handle, but prevent its reverse rotation by reason of their engagement with the serrations 26 and 27 as above specified. Obviously, the lock washer may be rigidly secured to the cap, if preferred, and in this case the serrations 27 of the latter, together with the dogs 31 may be omitted. The dogs 30 then cooperate with the serrations, or their equivalents, on the dome of the lever, as a single, instead of as a double-acting locking ratchet.

In Fig. 10 I have shown a further modification, in which the switch lever 16 has a finger end 32 slotted at 33 to afford a spring engagement with the attachment, which may be of either of the types above described. The normal diameter of the finger end being slightly greater than that of the engaging portions of the cap, the latter is gripped with a locking spring action and is held against accidental escape after adjustment.

In Fig. 11 I have illustrated an attachment of the type shown in Fig. 5 applied to the enlarged terminal ball 34 of a pull chain 35, the ball 24 being threaded at 36 to receive the threaded collar of the luminous cap.

A similar application of the invention is illustrated in Fig. 12, applied to the terminal ball 37 at the end of a switch cord 38, the ball 37 being threaded at 39. In this case the shoulder 40 of the ball forms an abutment against which the lower margins of the cap thrust when the cap is screwed down hard, and thus adds sufficiently to the frictional engagement between the cooperating threads to lock the cap in position.

Various other applications of the invention, and modifications of construction, will readily occur to those skilled in the art, which do not depart from what I claim as my invention.

I claim—

An attachment for an electric switch operating member having a peripheral threaded area and a radially serrated end, said attachment comprising a cap having a tapped recess to screw on the threaded area of the switch operating member, a lock washer secured in the bottom of said recess to engage the radial serrations at the end of the switch operating member, and luminous material at the opposite end of the cap.

In testimony whereof I have signed my name to this specification.

BENJ. C. PERKINS
